UNITED STATES PATENT OFFICE

BENJAMIN D. HARDESTY, OF BEAVER FALLS, PENNSYLVANIA, ASSIGNOR TO MAYER CHINA COMPANY, OF BEAVER FALLS, PENNSYLVANIA, A CORPORATION OF PENNSYLVANIA

SUPPORTING DEVICE FOR POTTERY

Application filed May 17, 1928. Serial No. 278,372.

My invention relates to the art of burning pottery or ceramic ware in kilns, and particularly to an improved ware support of the crank type. It has in view to provide such a support of minimum size and weight and so constructed as to enable a plurality of them to be used in series with economy of space, while supporting each piece of ware in the kiln independently, with ample 10 heat circulation space. Also, to provide for the ware a series of isolated stabilizing supporting points or edges, with interfitting engagement between adjacent supports ensuring maintenance of position during use. 15 The construction of the device and its manner of use and advantages are more fully hereinafter described.

Referring to the drawings:

Fig. 1 is a plan view showing the relative arrangement of the supports and ware;

Fig. 2 is a vertical sectional view on the line II—II of Fig. 1;

Fig. 3 is a perspective view of the support detached;

Fig. 4 is a front view showing the interfitting connection between the supporting terminals of the device;

Fig. 5 is a cross section on the line V—V of Fig. 2;

Fig. 6 is a perspective detail view of one of the supporting points.

In utilizing supporting devices of the kind involved, it is desirable to interpose between each piece of ware and the next adjacent piece, a support which will be spaced away from the ware sufficiently far to avoid contact except at a minimum number of locations and of as limited area as possible. Also, to generally conform to the contour of the ware and with ample transverse intervening space for circulation of the heating gases of the kiln.

While the particular shape of the supporting device transversely may be varied to adapt it approximately to the outline of the ware in cross section, it will be understood that the invention is not strictly limited to any particular extent of variation from a plane transverse area, or as to its size, dimensions, or shape. One common

form of ware is shown in the drawings, as a plate or dish 2, the middle portion of which is usually depressed below the surrounding rim or edge, and is ordinarily provided with the usual supporting rim or 55 bead 3 underneath.

Each of the series of supporting devices which carry a vertical series of ware pieces in the kiln, is made in skeleton form of a general comparatively flat tripod construction having three equilaterally arranged arms 4. These arms diverge from a middle flat portion 5, preferably provided with a middle triangular clearance opening 6, each arm sloping upwardly as at 7, and then 60 extending downwardly in the form of a vertical terminal foot piece 8. Each such foot piece is adapted to rest upon the upper edge portion of the next lower support, and 65 to provide, by its upper edge, a supporting bearing for the next upper support. 70

For the purpose of providing an interlock between the several pedestals 8, each is provided at its upper corner edge portion with a socket 9, adapted to receive and interfit with a lower projecting correspondingly narrower projection 10. 75

Projection 10 fits into socket 9 with slight clearance, each socket being shouldered inwardly and at each side laterally so that 80 when one support is placed upon another it will be held against lateral displacement, especially under the weight of the ware members 2 and the superimposed supports. 85

For the purpose of providing a point or knife edge bearing for the ware, or its lower supporting rim 3, each arm 4 is provided with a loosely mounted triangular supporting piece or bar 11, having three tapering edges. Each arm 4 is provided with a depression or socket 12 in its upper surface, shouldered and extending below the upper surface thereof so as to easily permit the insertion, with slight clearance, of one of the 90 supporting edged elements 11, in a position adapted to engage and carry the ware when placed thereon. Because of variations in diameter of the ware the edge pieces 11 are sufficiently long to provide such bearing at 100

their outermost, middle, or innermost portions, dependent on conditions.

The supports as thus made are composed of suitable refractory material as commonly utilized in the pottery art, and are simple in construction, cheap to manufacture, and durable. Because of their three-point bearings, both as to the support of the ware and supporting connection with each other, the supporting pieces are very easily assembled and taken apart, and provide a continuous supporting equilibrium both as to themselves and their burden. Due to their comparatively limited body section and weight, they have a corresponding limited heat absorptive value so that their removal from the kiln involves a minimum amount of heat subtraction therefrom. Their form contributes materially to the successful and economical operation of the kiln, both in manipulation, placement, and removal, while the interlocking construction ensures stability and avoidance of accidental breakage.

It will be understood that the device may be made in various sizes, proportions, shapes, etc., to adapt it to any particular design or shape of ware, and that various changes or modifications may be made in its detail construction by the skilled mechanic, without departing from the scope of the following claims.

What I claim is:

1. A supporting device for pottery ware consisting of a tripod shaped triple arm body of skeleton form having upwardly sloping ends with downwardly extending pedestals each provided with an upper socket and a lower lug, and having on the upper face of each arm a depressed rectangular shouldered bearing face for a separable ware supporting abutment, and an elongated abutment therein having a flat base seated in said bearing face with clearance at the ends and sides.
2. A supporting device for pottery ware consisting of an open center three armed frame of refractory material having a flat hollow depressed middle portion, a depressed shouldered seat on each arm, a triangular supporting elongated abutment in each of said seats, and terminal pedestals.
3. A supporting device for pottery ware consisting of an open center three armed frame of refractory material having a flat hollow depressed middle portion, a depressed shouldered seat on each arm, a triangular supporting elongated abutment in each of said seats, and terminal pedestals provided at bottom and top with interlocking rectangular male and female portions respectively, the male portion at the bottom of each pedestal being of its full width providing rectangular shoulders at each side for interfitting engagement in a corresponding upper socket of an adjacent similar pedestal.

4. In a ware support for saggers, a refractory carrier having plural radial horizontal face arms each provided on its upper face with a corresponding plurality of radially arranged depressed and shouldered seats, and corresponding triangular bars having flat bases freely seated therein with longitudinal and lateral clearance providing upwardly projecting contacting radially disposed edges for ware engagement.

5. In a ware support for saggers, an open center one-piece frame of refractory material having a depressed flat middle portion and three radiating arms, each sloping upwardly at its outer portion and then downwardly of uniform width providing terminal interfitting pedestals, the lower end of each pedestal being substantially rectangular with a middle shouldered extension, the upper portion of each pedestal having a corresponding rectangular depression for engagement of the shouldered extension of an adjacent pedestal, each radiating arm having in its flat portion adjacent the middle a radially disposed rectangular shouldered depression, and a supporting bar triangular in cross section resting by one of its flat faces in such depression with longitudinal and lateral clearance.

In testimony whereof I hereunto affix my signature.

BENJAMIN D. HARDESTY.
